ELECTRICAL TELEMETERING SYSTEM

Frederick J. Lingel, Bluffton, Ohio, assignor to
The Liquidometer Corporation, Long Island
City, N. Y., a corporation of Delaware

Original application August 23, 1940, Serial No.
353,783. Divided and this application October
31, 1944, Serial No. 561,284

4 Claims. (Cl. 177—351)

The present application relates to an electrical telemetering system by which data or indications having their origin at one point are transmitted to a distant point and there indicated on a suitable instrument.

The present application is a division of my prior and copending application Serial No. 353,783, filed August 23, 1940, entitled "Electrical instruments and systems, which application has now been abandoned and the subject matter thereof carried forward in a continuing application, Serial No. 567,848, filed December 12, 1944. The present application relates to the subject matter disclosed in the specification of my original application above identified and illustrated in Fig. 2 of the drawing thereof which is the same as the present figure of drawing. Only so much of the original disclosure as will afford a proper understanding of the subject matter shown in this figure is included in the present application. The claims of the present application are limited to subject matter readable on this figure as distinguished from claims readable on other figures of the parent application.

Certain features of the present invention are disclosed also in my patent entitled "Electrical translating instruments or devices," No. 2,339,021, granted January 11, 1944, which was copending with the above identified application Serial No. 353,783, of which this application is a division.

Among the objects of the present invention are to provide a telemetering system and particularly a receiver therefor, wherein an indicating pointer is caused to move through an arc which will usually be somewhat less than 180° and may be, for example, about 120° and particularly wherein the amplitude or total degree of arcuate swing of the pointer may be predetermined at a desired amount.

Other objects and advantages of my invention will be stated hereinafter or will appear to those skilled in the art upon reading the following description of the invention and of the manner and process of making, constructing, compounding, and using it, and I shall also explain herein what I now believe to be the principle thereof, and the best mode in which I have contemplated applying that principle.

Desiring to have it understood that my invention may be carried out by other means and with other apparatus, and that it may be used in other environments and for other purposes, I shall now proceed to describe what I now consider to be a preferred form of apparatus for practicing the invention.

Referring to the drawing:

The single figure of the drawing is a wiring diagram in which the electrical connections are such that the normal scale deflection produced by two coils may be varied by the use of a third coil, which may be differentially wound.

It will be understood that while there is illustrated in the drawing and described hereinafter a wiring diagram and while the drawing shows diagrammatically only certain structural features of the invention, this structure, particularly the receiver of the telemetering system, may be constructed in any recognized and known way applicable to telemetering systems of this general type, that is, systems wherein the receiver includes a rotor or one or more parts carried thereby and permanently magnetized transverse to its axis of rotation. The rotor thus constructed rotates freely within a structure having associated therewith outside the rotor a plurality of coils which will set up a magnetic flux influencing the position of the rotor. Such a structure is disclosed, for example, in my parent application Serial No. 353,783, of which the present application is a division. Inasmuch, however, as these structures, from a broad point of view, are known in the art, it has not been thought necessary further to illustrate or describe them in detail in the present application.

Referring now particularly to the accompanying drawing, I have shown a combination wherein a receiver is provided having a rotor generally indicated at 10, which as has been set forth is adapted to be permanently magnetized transverse to its axis of rotation and which is suitably mounted in anti-friction bearings and carries rigid therewith a pointer 28 adapted for visual cooperation with a scale diagrammatically indicated at 28. For the purpose of influencing the position of the rotor 10 and hence that of the pointer 28, there are provided two coils 32, which are arranged preferably at about 120° to one another and with their axes substantially radial in respect to the rotor (the upper coils shown on the drawing). It will be understood that these coils are located outside the peripheral boundary of the rotor 10 in the receiving instrument and are connected as shown in the drawing. A third coil, also generally designated at 32 but including two portions 132 and 232, is shown diagrammatically on the accompanying drawing. This coil is preferably also disposed as described for the other coils 32, that is, outside the peripheral boundary of the rotor 10 and with its axis substantially radial in respect thereto. As

shown, it is disposed at an angle of about 120° with respect to each of the other two coils. The lower or vertically disposed coil 32, including the coil portions 132 and 232 is provided for the purpose of controlling or predetermining the amplitude of movement of the pointer 26 under the influence of the first named coils 32. For this purpose the two sections 132 and 232 are preferably wound in opposite directions, so as to oppose one another. By connecting coil 32 to a source of E. M. F. and by providing more turns in one of the opposing sections 132, 232 than in the other of said sections, the full scale deflection of the pointer 26 may be made greater or less than 120° to an extent depending upon the difference between the numbers of turns in the two sections. When the number of turns of either section 132, 232 is greater than that of the other of said sections, the electrical connection of the differential coil 32 (132—232) with respect to the other two coils 32, 32 determines whether the full scale deflection of the pointer 26 is greater or less than 120°. If the predominant effect of the coil combination (132—232) is bucking with respect to the other coils 32, 32, the full scale deflection will be less than 120° to an extent, as stated above, depending upon the difference between the numbers of turns of the two sections 132, 232. On the other hand, if the predominant effect of the coil combination (132—232) is cumulative with respect to the other coils 32, 32, the full scale deflection will be greater than 120° to an extent depending upon the difference between the numbers of turns of the two sections 132, 232.

As shown, the instrument is adapted to be actuated to indicate the level of a liquid in a container. For this purpose as is diagrammatically illustrated, there is provided a float 50, which is arranged to float upon a liquid indicated diagrammatically in the drawing, this float being carried by an arm 48. This arm is suitably arranged in a manner known to the art to vary the position of a contact member 46 along a resistance strip or potentiometer coil 82. The connections are such that the instrument just described will indicate by the position of the pointer 26 with respect to the scale 28 the position of the contact 46 along the resistance strip 82, which in turn is responsive to the level of the liquid as indicated by the position of the float 50.

While the system has been diagrammatically illustrated to indicate liquid level in a container, it will be understood that any other condition suitably arranged to actuate a movable element, which may be an electrical contactor and which contactor is movable along a resistance strip or potentiometer coil as shown at 82, may be similarly indicated by the system of the present application. This application is therefore, not intended to be limited to liquid level indication. The resistance strip 82 is electrically connected across the line 172 (preferably through a resistance 83 hereinafter described) supplied by a suitable source of direct current E. M. F. The float controlled contact member 46 is electrically connected to the outer end of the upper right hand coil 32 and to the inner end of the upper left hand coil 32. The outer end of the upper left hand coil 32 is electrically connected to the upper end of the resistance strip 82 and to the inner end of the composite coil 32 (132—232). The inner end of the upper right hand coil 32 is electrically connected to the lower end of the resistance strip 82 and to the outer end of the composite coil 32 (132—232).

Whatever the selected full scale deflection may be, the scale 28 is so calibrated and the design is such that the pointer 26 will indicate upon the scale 28 the remote liquid level indicated by the float 50 or such other condition as may be suitably connected thereto in a way which will be apparent to those skilled in the art.

In order that short circuits across the line 172 at the transmitting station, or between the transmitting station and the indicating instrument, shall not damage the battery or so reduce its terminal E. M. F. as to render the operation of other instruments connected to the same line or source inaccurate and unreliable, I provide a protective resistance 83, mentioned above, and connected as shown. The resistance of this element 83 is such, with respect to the electrical constants of the rest of the system, as to prevent the undesirable consequences, spoken of above, that might otherwise result.

While other electrical constants may be employed, I have found that the following will give satisfactory results for a desired scale deflection less than 120°. The resistance of the resistor 82 is 200 ohms and that of the protective resistor 83 is 150 ohms. Each coil 32 has 1600 turns and a resistance of 450 ohms. One of the coil sections 132, 232 has 900 turns and the other 700 turns, with the predominant effect bucking with respect to the other two coils 32, 32. The E. M. F. at 172 is twelve volts.

In some cases and by proper selection of electrical constants, more than one indicator may be reliably controlled by the same transmitter by connecting the indicating instruments in parallel. For example, as shown in the drawing, a second receiving instrument which may be identical with that hereinabove described and diagrammatically illustrated in the drawing, may be electrically connected in parallel therewith across the leads or conductors 90 and the positive side of the current supply line 172. Reliability in indication has been attained in such use of a plurality of indicating or receiving instruments by virtue of the comparatively high resistance of the coils 32 and 132, 232 with respect to the resistance of the potentiometer or resistor 82.

While I have shown and described but one embodiment of the present invention, it is understood that the principles herein disclosed may advantageously be used in other physical embodiments thereof. I do not wish to be limited, therefore except by the scope of the appended claims, which are to be construed validly as broadly as the state of the prior art permits.

What is claimed is:

1. An indicating instrument comprising, in combination, a permanently magnetized cylindrical rotor, and a plurality of angularly spaced coils mounted with their flux axes radial with respect to said rotor, one of said coils having mutually opposing windings for varying the range of actuation of said rotor by the other coils, said windings having an unequal number of turns, a source of E. M. F., and means including a potentiometer for variably energizing said coils from said source of E. M. F.

2. An indicating instrument including a permanently magnetized rotor and a plurality of coils angularly spaced around said rotor and each having its axis radial with respect to said rotor, one of said coils having unequal opposing coil sections, electrical connections for supplying the last mentioned coil with substantially constant current from said source of E. M. F., and elec-

trical connections including a control device for supplying the other coils with variable current from said source of E. M. F.

3. An indicating instrument, comprising a rotor permanently magnetized in a direction transverse of its axis of rotation, at least two coils disposed with their axes at substantial angles to each other and spaced radially from the axis of rotation of said rotor, electrical connections and a source of E. M. F. for transmitting variable currents to said coils and thereby for controlling the angular position of said rotor within a total amplitude of movement of less than 180°, and another coil disposed in magnetic association with said rotor, and means connecting said other coil to a sub-

stantially constant source of E. M. F. which is independent of the current variations in the first named coils for controlling the amplitude of the angular movement of said rotor under the influence of the first-named coils.

4. An indicating instrument in accordance with claim 3, wherein the first-named coils comprise two coils with their axes radially disposed in respect to said rotor and at an angle of about 120° to one another, and wherein said other coil is disposed with its axis radial of said rotor and at an angle of about 120° to each of the first two-named coils.

FREDERICK J. LINGEL.
